(57) **CLAIM**

The ornamental design for a supporting system for electric fence wire, as shown and described.

DESCRIPTION

FIG. 1 is a front elevational view of a supporting system for electric fence wire showing my new design;

FIG. 2 is a rear elevational view thereof;

FIG. 3 is a bottom plan view thereof;

FIG. 4 is a top plan view thereof;

FIG. 5 is a right side elevational view thereof;

FIG. 6 is a left side elevational view thereof;

FIG. 7 is a reduced top left side perspective view thereof;

FIG. 8 is a front elevational view of a second embodiment of a supporting system for electric fence wire showing my new design;

FIG. 9 is a rear elevational view thereof;

FIG. 10 is a bottom plan view thereof;

FIG. 11 is a top plan view thereof;

FIG. 12 is a right side elevational view thereof;

FIG. 13 is a left side elevational view thereof; and,

FIG. 14 is a reduced top left side perspective view thereof.
